UNITED STATES PATENT OFFICE.

CURTIS HUSSEY VEEDER, OF HARTFORD, CONNECTICUT, ASSIGNOR TO THE VEEDEER MANUFACTURING COMPANY, OF HARTFORD, CONNECTICUT, A CORPORATION OF CONNECTICUT.

ODOMETER.

SPECIFICATION forming part of Letters Patent No. 741,420, dated October 13, 1903.

Application filed February 7, 1903. Serial No. 142,303. (No model.)

To all whom it may concern:

Be it known that I, CURTIS HUSSEY VEEDER, a citizen of the United States, residing in Hartford, county of Hartford, in the State of Connecticut, have invented certain new and useful Improvements in Odometers, of which the following is a specification, reference being had to the accompanying drawings, forming a part hereof.

10 This invention relates to registering devices, and particularly to such devices as odometers, revolution-counters, and other instruments of like general character.

One object of the invention is to provide 15 an instrument of this class which shall be substantially impervious to dampness and dust, such as often finds its way into these instruments when they are continuously exposed to rain and mud, to the serious injury 20 of the counting mechanism.

Another object of the invention is to permit the use of a relatively stout shaft, to 25 which the star-wheel or actuated member of the instrument is secured and in operative relation with which a braking device is provided to prevent the spinning of said shaft when the star-wheel is actuated in rapid succession. By employing a large and substantial main shaft an adequate braking device 30 may be used.

A further object of the invention is to make the counter mechanism of the instrument reversible with respect to the case inclosing the same in order that the case may be attached 35 to a vehicle, for instance, or to any other support in the most convenient manner and still be in a position to be easily observed.

In general the object of the invention is to produce an odometer or like instrument 40 which under varying conditions of use shall be accurate, durable, and not liable to get out of order.

In the accompanying drawings, Figure 1 is 45 a plan view of an instrument embodying the invention. Fig. 2 is a view in side elevation. Fig. 3 is a view in central longitudinal section, illustrating the connection with the counter, which is shown in elevation. Fig. 4 is a view, partly in transverse section, taken 50 on a plane indicated by the broken line 44

in Figs. 1 and 3, a portion of the spring carrier-block and adjacent washer being broken away to show the adjacent friction-disk. Fig. 5 is a plan view of the base portion of the casing with the braking mechanism and main 55 shaft removed therefrom. Fig. 6 is a view in longitudinal section of the base portion of the casing, taken on a plane indicated by the broken line 66 in Fig. 5. Fig. 7 is a detail view, partly in section, showing the relation between the shaft, the friction disks and washers, and the spring carrier-block. Fig. 8 is a view in central longitudinal section of a modification of the instrument with the 60 braking device omitted; and Fig. 9 is a similar view of still another modification, showing the braking device separated from the counting mechanism.

One of the component parts of the odometer is the counter or registering mechanism 70 a; but with the construction of such counter or registering mechanism the present invention is not concerned. It may accordingly be of any suitable construction and is herein-after regarded and referred to as a unitary 75 element. As has already been stated, however, one of the objects of this invention is to protect this mechanism, as well as the entire interior of the case of the instrument, from the harmful effects of moisture and dust, and 80 for this purpose a peculiarly-constructed casing for the entire odometer mechanism is provided and comprises in general two parts—a base b and a cap c. The counter or registering mechanism is fitted and secured in the 85 top of cap c, which is of a suitable shape to receive the same and is provided with a crystal hermetically sealed in the top and through which the readings of the counter or registering mechanism may be observed.

The base b is a strong and substantial casting having a base-plate with holes b' therein to receive a U-bolt or other fastening and upright extensions d formed upon said base-plate, which extensions constitute a chamber 95 or inclosure e for the main shaft and braking device. The cap c fits very closely over and around these extensions d, which form the walls of the inclosure e, and down upon the base-plate, thereby preventing any moisture 100

or dirt from entering the interior of the casing except around the edges of the cap, whence it must travel up and over around the base extensions *d* before it can reach any 5 of the odometer mechanism. Even then the counter, which is in the upper part of the cap, will not be reached by the moisture, and, as is obvious, said counter will be protected until the odometer-casing is literally flooded 10 with water.

The main shaft *f*, to which the star-wheel or actuated member *g* is keyed, is journaled in the extended part of the base *d*, bearings *h* being formed therein for the reception of 15 said shaft, while the bearing next the star-wheel is extended somewhat to resist the lateral thrust of the shaft *f* when the odometer is run at high speeds. Said shaft is locked in the odometer-casing by a key *i*, which fits 20 in a peripheral groove or keyway on the end of the shaft, and a dust-cap *j*, containing suitable packing *j'*, is provided around the shaft between the star-wheel and the casing to prevent the entrance of dirt or moisture 25 into the instrument at that point.

Mounted upon the main shaft and secured to the same so as to rotate therewith is a pinion *k*, which engages a similar pinion *l*, keyed to the shaft of the counter or registering mechanism. Also mounted upon the main shaft so as to rotate therewith and to be movable longitudinally thereon are disks *m*, preferably of steel, and in alternation with said disks are friction plates or washers *n*, 35 preferably of fiber, said friction-plates being squared to fit the chamber *e* and being held thereby from rotation. These disks and friction-washers constitute a braking device for preventing the star-wheel and shaft from 40 spinning when the star-wheel is actuated in rapid succession. Suitable means are provided for keeping said disks and washers in close contact, such means being preferably a set of springs *o*, seated in a spring carrier-block *p*, fixed to the sides of the casing. Said springs bear against one of the washers *n* at one end of the braking device, while a plate *q*, fixed to the sides of the casing, is provided at the other end of the device and 45 receives the thrust of the springs *o*.

In order to secure the disks *n* to the shaft *f* in the manner above stated, said shaft is formed with one or more longitudinal grooves or keyways *f'* and the disks with corresponding projections *m'*, adapted to fit in said grooves. In the same manner it is preferable to secure the pinion *k* to said shaft. In assembling the parts of the odometer the pinion *k*, thrust-plate *q*, disks *m*, friction-washers *n*, and spring carrier-block *p* are first placed in their respective positions in the chamber or inclosure *e* and then shaft *f* inserted through the openings in the center of all of said parts, the keyways *f'* in said shaft 60 receiving the projections on the disks *n* and pinion *k*. The shaft is then locked in position by the key *i*. Inasmuch as the chamber

e, as well as the upper part of cap *c*, are symmetrical, the positions of the braking mechanism, pinion *k*, and the counter or registering mechanism *a* with respect to the casing may be reversed—that is, the positions of the pinion *k* and thrust-plate *q* on the one hand and the spring carrier-block *p* on the other hand may be interchanged and the counter *a* so 70 placed in the top of cap *c* as to cause pinion *l* to engage pinion *k* in its new position. Because of this reversibility of the mechanism of the instrument it becomes possible to mount the instrument with respect to the actuating member—the wheel of the vehicle, for instance—in two different positions with respect to said member or wheel, while the readings of the counter are visible in an upright position from either side of said member or 80 wheel, as may be desired. When the instrument is in operation, motion is transmitted from the actuating member, usually a pin on the spoke of a vehicle, intermittently to the star-wheel, and said wheel is in rotation only 85 during the time that the pin and the star-wheel are in contact, the braking mechanism causing said wheel to stop as soon as the pin or actuating member becomes disengaged 90 from the star-wheel.

In a modification of the odometer shown in Fig. 8 the star-wheel has been omitted, inasmuch as this form of the instrument is designed to be actuated by some suitable mechanism for supplying a continuous motion to 100 the main shaft *f* instead of intermittently, as in the previous case. The braking device has also been omitted, as the shaft *f* is at all times directly connected with the actuating member, and therefore is not left to spin freely 105 when the instrument is running at a high speed. If the counter or registering mechanism in this modification is similar to that in the form of the instrument first described, means for effecting the proper speed reduction should be interposed between the main shaft and the shaft of the counter. This speed reduction may be effected simply by increasing the size of the pinion *l* on the counter-shaft and by reducing the size of pinion 110 *k* on the main shaft, the ratio of the sizes of 115 the two pinions shown in the drawing Fig. 8 being five to one.

In Fig. 9 still another modification of the instrument is shown. Here the counter mechanism (not shown) is separated from the main shaft and placed in a location where it may be conveniently observed, being connected to the main shaft by a flexible shaft or some other suitable means for transmitting motion. 120 The braking device, the main shaft, and the star-wheel are similar to those already described with reference to the first form of the instrument above referred to, while the cap *c*, which no longer contains the counter mechanism, is made to conform substantially to 125 the shape of the chamber or inclosure *e* of the braking mechanism.

I claim as my invention—

1. In an odometer, the combination of a casing comprising a cap and a base, a counter in the upper portion of the cap, a case inclosing said counter, and mechanism for actuating the counter mounted upon the base. 5
2. In an odometer, the combination of a casing comprising a cap and a base, a counter in the upper portion of the cap, a case inclosing said counter, a shaft mounted on the base, and operative connections between the counter and the shaft. 10
3. In an odometer, the combination of a base, upright extensions integral with said base and forming a chamber, a cap adapted to fit closely upon and entirely inclose the extensions, a counter inclosed in the upper portion of the cap, and mechanism for actuating the counter mounted within the chamber. 15
4. In an odometer, the combination of a base, upright extensions integral with said base and forming a chamber, a cap adapted to fit closely upon and entirely inclose the extensions, a counter inclosed in the upper portion of the cap, a shaft journaled in the extensions, an extended bearing for said shaft formed upon the base, and operative connections between the counter and shaft. 20
5. In an odometer, the combination of a casing comprising a cap and a base closed against the entrance of dust or dirt, and a counter in the upper portion of the cap, all the joints between the cap and the base being below the counter. 25
6. In an odometer, the combination of a casing comprising a cap and a base closed against the entrance of dust or dirt, and a counter in the upper portion of the cap, and a casing inclosing said counter, all the joints between the cap and the base being below the counter. 30
7. In an odometer, the combination of a casing, a shaft extending into the casing, a friction-brake within the casing in operative relation with the shaft, a counter within the casing, and mechanism for actuating the counter operatively connected with the shaft. 35
8. In an odometer, the combination of a casing, a main shaft extending within the casing, a friction-brake within the casing in operative relation with said shaft, a counter within the casing, a shaft for said counter, and operative connections between the main shaft and the counter-shaft. 40
9. In an odometer, a casing therefor, a shaft extending through the casing, an extended bearing formed in the casing for one end of said shaft, braking mechanism within the cas- 45
- ing in operative relation with said shaft, a counter, and mechanism for actuating the counter operatively connected with the shaft. 60
10. In an odometer, a main shaft, a counter operatively connected with the shaft, and braking mechanism in operative relation with the shaft, said mechanism comprising a plurality of disks longitudinally movable upon the shaft but keyed thereto so as to rotate therewith, and a stationary friction-plate between adjacent disks. 65
11. In an odometer, a main shaft, a counter operatively connected with the shaft, and braking mechanism in operative relation with the shaft, said mechanism comprising a plurality of disks longitudinally movable upon the shaft but keyed thereto so as to rotate therewith, a stationary friction-plate between every adjacent disk, and means to hold the friction-plates and the disks in contact. 70
12. In an odometer, a main shaft, a counter operatively connected with the shaft, and braking mechanism in operative relation with the shaft, said mechanism comprising a plurality of disks longitudinally movable upon the shaft but keyed thereto so as to rotate therewith, a stationary friction-plate between every adjacent disk, and springs to hold the friction-plates and the disks yieldingly together. 80
13. In an odometer, the combination of a symmetrical casing comprising a cap and a base, a shaft journaled in said casing, a counter in the upper portion of the cap, the joints between the cap and the base being below the counter, and shiftable connections between said shaft and counter. 85
14. In an odometer, the combination of a symmetrical casing, a shaft journaled in said casing, a reversible counter, a pinion on said counter, a pinion in operative relation with the first-named pinion and keyed to said shaft so as to be shiftable longitudinally thereupon. 90
15. In an odometer, the combination of a symmetrical casing, a shaft having a longitudinal keyway journaled in said casing, a reversible counter, a pinion on said counter, a pinion on said shaft in operative relation with the first-named pinion and having a key engaging said keyway whereby it can be shifted longitudinally upon the shaft. 100

This specification signed and witnessed this
2d day of February, A. D. 1903.

CURTIS HUSSEY VEEDER.
